CONTAINER

George C. Erb, Forest Hills, N. Y., assignor to
 American Can Company, New York, N. Y., a
 corporation of New Jersey

Application May 18, 1939, Serial No. 274,437

4 Claims. (Cl. 220—77)

The present invention relates to the reenforcement of containers or cans and has particular reference to an improved structure in the side seam joint of sheet metal can bodies.

An object of the invention is the provision, in a sheet metal can body, of a side seam having portions cut along a tessellate line and formed into a series of alternate long and short hooks which are interfolded to produce a side seam of increased strength for a hermetically sealed can, such can resisting high external pressure tending to collapse the body, as in vacuum packed cans, and also which resists high internal pressures that develop in cans used for beer, carbonated or other liquids.

Another object is the provision of a reenforced side seam for metal can bodies the blanks of which are cut from a web or strip in a single line of severance which separates adjacent body blanks with complementary edges, such a line of cut having rectangular notches and rectangular lugs extending in alternate fashion on opposite edges of the can body blank these lugs being interfolded into lock side seams possessing maximum strength and being pressure resistant.

A still further object of the invention is the provision of a reinforced soldered side seam embodying a series of alternate long and short hooks which are interfolded in the side seam prior to soldering.

Numerous other objects and advantages of the invention will be apparent as it is better understood from the following description, which, taken in connection with the accompanying drawing, discloses a preferred embodiment thereof.

Referring to the drawing:

Figure 1 is a top plan view of a strip of stock showing how two or more identical can body blanks with complementary edges are cut along a tessellate line of severance;

Fig. 2 is a fragmentary view along the side seam edges of a body blank at an enlarged scale and showing the alternate rectangular lugs and notches folded back and arranged for hooking engagement;

Fig. 3 is a similar view showing the hooks interlocked as indicated by dotted lines into a double seam joint;

Fig. 4 is an enlarged fragmentary sectional view taken substantially along the line 4—4 of Fig. 2, showing a long and short hook;

Fig. 5 is a sectional view taken along the line 5—5 in Fig. 3 and drawn to the same scale as Fig. 4 showing the long and short hooks inter-

folded and soldered together, the short hook extending from the outer fold; and

Fig. 6 is a sectional view taken along the line 6—6 in Fig. 3 and drawn to the same scale as Figs. 4 and 5 showing the long and short hooks united and soldered together, the long hook extending from the outer fold.

In order to illustrate a preferred embodiment of the invention, Fig. 1 indicates a strip of stock 11 cut from a larger piece of material to a width equivalent to the height desired for a can body and of sufficient length to cut a plurality of can body blanks 12. The strip stock 11 may be uncoated on one or both sides or printed or lithographed as in decorated cans.

The can body blanks 12 (Fig. 1) are cut to the desired length by a transverse cut 13 along a line having tessellate form and of a complementary arrangement to produce a series of alternate lugs 14 and a series of notches 15 oppositely disposed on the edges of the same blank. The edge on one blank therefore is a complement of the opposite edge of an adjoining blank. A substantial saving in material is hereby realized which would otherwise be wasted where the blanks are cut from separate pieces of stock large enough to provide for the usual side seam joint.

Each individual body blank 12 upon being severed from the web or strip of stock 11 may then be passed through the usual body forming operations. This is conveniently done in an automatic body making machine.

A notching operation is first performed upon the two ends of the blank. In the present instance the serrated edges of the blank are merely notched adjacent the sides of the blank and at each end. On one side a portion of the metal is removed by notching the blank near each end of the edge leaving two tongues 17 (Fig. 2) the inner edges of which are formed by angular lines 18. On the opposite edge of the blank two notches are cut adjacent each end of the edge leaving a tongue 21 having an inner angular edge 22 and an outer angular edge 23.

The notched blank may then be rolled into cylindrical or body form by rollers, this being a preferred way of making can bodies. This forming of the body places it over a horn the edges being slightly separated. It is moved longitudinally into an edging station where the intermediate section of each edge of the cylindrical body which contains the lugs 14 and notches 15 is bent into opposite directions along lines of bend 24 this forming oppositely disposed long hooks

25 (Figs. 2 and 4) and short hooks 26. This bending or edging action locates the long and short hook as indicated in Fig. 2. One bent edge of the body is shown to the left in full lines in this figure and the other bent edge is indicated by dotted lines as shown to the right.

The edged but incompletely formed body is then brought into can body size by its oppositely disposed hooked edges being interlocked in the usual manner. In interlocking the hooked edge of the body each tongue 17 provides the inner member of the lapped section of the seam being inside of and against the tongues 21 which form the outer members. After interlocking the seam is bumped in order to close in all interlocked portions to produce the side seam shown in Fig. 3. In this intermediate hooked or locked section of the bumped seam three and four thicknesses of the body wall result when viewed in cross section.

Fig. 5 shows one such cross section and it will be observed that the left half of the seam is of three thicknesses. In the right half there is the usual fully hooked four thicknesses of seam. The three thickness section is to the left of a short hook 26, the body wall adjoining a long hook 25 at this position having been pressed down tightly as at 27 in the bumping operation. This pressing action produces a locking step 28 in the long hook 25.

In Fig. 6 the cross section of an alternate arrangement of parts shows the four thickness section formed on the left half of the seam by interposing the short hook 26 between the can body 12 and the end of the long hook 25. The three thickness section is formed at the right half of the seam by pressing together, during the bumping operation, the body wall region as at 29. This pressed region 29 along the hooked seam locks against a stepped portion 31 formed on the long hook 25.

The resulting side seam embodying this alternate locking arrangement, (Figs. 3, 5 and 6) when soldered, is of greatly increased strength. Such an improved joint resists high external pressures which tend to collapse vacuum cans and others that are subjected to vacuumizing and gassing during the canning processes. Such a joint also resists high internal pressures which may develop in a sealed can. The abutment of the end of the long hook 25 within the short hook 26 (Figs. 5 and 6) together with the locking effect of the stepped portions 28 and 31 give this double holding result.

The folding of the edges of the blank, the interlocking of the long and short hooks and the pressing together of the seam sections, as just described, are all done automatically during the manufacture of the can at various stations in the body maker.

The introduction of the solder (indicated by the numeral 32) is from the outside in the usual manner and may be an operation within or closely associated with the body maker. The distribution of the solder in the finally prepared seam is clearly illustrated in Figs. 5 and 6. The solder fills all the voids of the lock seam section and fills in between the end laps at the engaged parts 17 and 21. The spaces between adjacent long and short hooks serve as vents and permit the hot gases of the soldering operation to escape from the seam interior while the solder is flowing into and closing all of the interstices of joint. This venting produces a better bonded soldered seam.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A reenforced metallic can body capable of resisting both high internal and external pressures, which comprises a can body formed from a metal blank having tessellated edges at its ends, said edges being bent into alternate oppositely disposed long and short hooks interlocked together with a long hook interfolded with a short hook, said hooks being held by solder interposed therebetween.

2. A reenforced metallic can body capable of resisting both high internal and external pressures, which comprises a can body formed from a metal blank having rectangular notches and rectangular lugs alternately arranged along opposed marginal edges one of said edges being complementary to the other edge said marginal edges being bent into alternate oppositely disposed long and short hooks interlocked together with a long hook interfolded with a complementary short hook, said hooks having solder interposed therebetween to form a hermetic side seam.

3. A reenforced metallic can body capable of resisting both high internal and external pressures, which comprises a can body formed from a metal blank having rectangular notches and rectangular lugs alternately arranged along opposed marginal edges, said marginal edges being bent in opposite directions to form oppositely disposed long and short hooks, a long hook being interlocked with a short hook, said hooks forming a plurality of interengaging oppositely disposed holding elements, a part of each long hook on one side of the seam being pressed together to form a stepped shoulder having abutted engagement against its interlocked short hook, all interlocked parts being held together by solder in a hermetic joint.

4. A reenforced can body capable of resisting both high internal and external pressures, which comprises a can body having a soldered side seam, opposed marginal edges of the body within the seam region constituting oppositely disposed alternated long and short hooks, a long hook being interlocked with a short hook, said interlocked hooks forming a plurality of interengaging holding elements arranged inside of the can body, a part of each long hook on the inside of the seam being pressed outwardly into closed form and constituting with the adjacent inside wall of the body a three thickness section, leaving a stepped shoulder where the pressed-in part connects with the other part of said long hook and providing an abutment against its interlocked short hook and forming a four thickness section in the seam, the alternated arrangement of said pressed in long and abutted short hooks providing alternate three thickness and four thickness sections extending longitudinally of the side seam, the interlocked parts being held together by solder in a hermetic joint.

GEORGE C. ERB.
